HEATER FOR SHOE FILLERS

Melvin O. Jennings, East Lexington, Mass., assignor to Harry H. Beckwith, Brookline, Mass.

Application November 8, 1930, Serial No. 494,316
Renewed August 17, 1933

9 Claims. (Cl. 219—35)

This invention relates to a heater for conditioning shoe filling material which is composed of ground cork or the like mixed with a thermoplastic binder. Shoe filler materials of this type are in wide use and are employed to fill the shallow cavity on the under face of the inner sole of a shoe, this cavity being defined by a surrounding ridge on the welt of the shoe. Filler of this type is customarily applied to the bottoms of partly made shoes by an operator using a tool somewhat similar to a putty knife. In order to facilitate the operation of applying shoe filler, the filler is customarily heated to a sufficient temperature to render it loose and of a somewhat mealy consistency so that a portion can be scooped up on the knife blade and molded into the recess in the shoe bottom by a sweep of the blade. It is an object of this invention to provide a heater adapted to condition the blocks or loaves of cold filler which may be placed therein, and to present the conditioned filler in a convenient and accessible position for the operator. It is a further object of the invention to provide apparatus which is simple and efficacious and which cannot injure the filler by overheating. Other advantageous features of the invention will be apparent to one skilled in the art from the disclosure thereof in the following description and on the drawings, of which,—

30 Figure 1 is a front elevation of apparatus embodying the invention.

Figure 2 is a side elevation of the same.

Figure 3 is a fragmentary section of the same in a sectional plane.

35 Figure 4 is a section of the apparatus on the line 4—4 of Figure 1.

Figure 5 is a fragmentary section on the line 5—5 of Figure 4.

Figure 6 is a section on the line 6—6 of Figures 40 2 and 4.

Figure 7 is a section on the line 7—7 of Figure 4.

Figure 8 is a fragmentary section on the line 8—8 of Figure 1.

45 Figure 9 is a fragmentary section showing a modified form of wall structure.

Figure 10 is a wiring diagram of the heating circuits of the apparatus.

Referring to the drawings in detail, the apparatus 50 comprises a reservoir 20 adapted to hold a considerable quantity of shoe filler. This reservoir is provided with a suitable lid or cover 21 at the top thereof and opens into a basin 22 below and in front thereof. I have discovered that 55 conditioned shoe filler is far less liable to stick to a smooth Monel metal surface than it is to other metal surfaces. Hence the reservoir and basin are preferably made in such a way as to present smooth Monel metal surfaces to the filler contained therein. This facilitates a gravity

feed of filler from the reservoir into the basin. The bottom or floor 23 of the reservoir is preferably of Monel metal and is sloped so that filler material, after being conditioned, tends to flow from the reservoir 20 into the basin 22. The basin 65 may be provided with a cover 24 to conserve the heat within the basin and container when the former is not in use. This cover may be folded back on suitable hinges 25 to present the filler in the basin to the operator. As indicated in Figure 70 4, side walls of the reservoir 20 include three spaced shells of sheet metal, some or all of which may be corrugated for strength as shown in Figure 8. The space between the outer shell 26 and the middle shell 27 is preferably filled with a 75 suitable heat insulating material 30. This may be ground cork, fiber, or any other material suitable for the purpose. Between the middle shell 27 and the inner shell 31 is a space 32 partly filled with a liquid, such as oil or water, for transferring distributing heat from the heaters to the inner surfaces of the reservoir and basin. Thus an insulated jacket for the liquid is provided on all four sides and also on the bottom of the reservoir 20. The inner shell 31 is preferably of 80 Monel metal and is spaced only about half an inch from the middle shell 27. This is sufficient to permit free circulation of liquid therein, but reduces to a minimum the quantity of liquid to be heated for warming the interior of the basin 90 and reservoir. Two sides and bottom of the basin may thus be heated, but the front wall of the basin is preferably unheated, this wall having only the heat insulating layer between shells for the comfort and protection of the operator who 95 stands close to the front of the basin. To augment the heating effect of the side walls I may increase the heated area presented to the contents of the reservoir by installing within the reservoir a heated member 33 which preferably projects upwardly from the bottom of the reservoir, and which may also project laterally from a side thereof. As shown in Figure 6, this additional heating member may be in the form of a wedge extending forwardly from the rear wall of 100 the reservoir to approximately the center of the reservoir. This structure carries the heat into the center of the mass of filler and thus aids materially in maintaining the entire mass of filler at the desired temperature. The member 33 is 105 made with a double wall forming a jacket communicating with the jacket around the sides and bottom of the reservoir. The inner shell or lining of the member 33, which is presented to the filler, is preferably made of Monel metal to avoid sticking of the filler thereto. The jacket on the bottom of the reservoir is heated directly by any suitable means, such as steam pipes or electrical units which may be secured against the outer shell of the bottom jacket. The liquid heated in 110 115 120

the bottom jacket circulates freely by gravity up through the side walls and the central column.

In order to regulate the heating of the liquid, I may provide a suitable thermostat 42 having a bulb 43 inserted in the jacket 36 at any convenient point. The thermostat may be set to operate at any desired temperatures. For example, it may be set to close a heating circuit when the temperature of the liquid falls to 204° F., and to open the circuit when the liquid rises to 208° F. This is sufficient to keep ordinary commercial thermoplastic shoe filler in proper condition for use with no danger of "burning" or harming the filler. As indicated in Figure 10, the thermostat 42 may be employed to turn on and off a relatively powerful heating unit 44 to augment the heating effect of a smaller unit 45 which is turned on and off only by the main switch 46. The latter is a single on-and-off switch by which the current for the entire apparatus is turned on and off.

If a liquid such as a suitable oil be used in the jacket surrounding the reservoir, the vaporization of the liquid at the operating temperatures of the heater will be negligible so that the supply of oil in the jacket will ordinarily need to be replenished only at long intervals. The use of a suitable oil is also advantageous because with its use the thermostat can be set to maintain a temperature higher than the atmospheric boiling point of water. Higher temperatures can thus be maintained for special kinds of shoe filler which may require them. Moreover, I have found that the heat transfer from the heating units to a suitable oil, such, for example, as a light mineral oil, is especially efficient, as is also the transfer of heat from such oil to the lining of the reservoir. Thus when the heater is turned on at the beginning of the day's work, the efficient distribution of the heat to the interior of the reservoir and basin quickly conditions the filler therein. In case it is desired to use water or other liquid liable to evaporate, I may provide an auxiliary tank 50 which may be attached to a side of the reservoir 20 and may communicate with the jacket as by a passage 51 near the bottom of the tank. A vent 52 may lead from the jacket into the upper part of the tank to permit the escape of vapor which may rise from the warmed liquid in the jacket. Since the liquid need be heated only to a temperature well below the atmospheric boiling point of water, the loss of water during operation is slight.

In order to assist the operator in smoothing and packing the filler which has been inserted in a shoe, a heating roll 60 may be mounted on a cross bar 61 which is carried by a pair of uprights 62, 63. The roll 60 is preferably provided with an internal heating unit such as an electrical resistance unit by which it is maintained at a suitable temperature as soon as the current is turned on in the circuits of the apparatus. Mounted adjacent to the roll 60, or in any other suitable or convenient position, is a knife block 65 adapted to receive the blades of knives and to heat these blades to prevent sticking of the filler thereto and to facilitate the spreading of a filler in the shoe.

I claim:

1. Apparatus for conditioning shoe filler, which comprises a reservoir having a forwardly sloping bottom, a basin projecting forwardly from the lower part of said reservoir, a thin jacket for liquid on the sides and bottom of said reservoir, means for maintaining said jacket substantially filled with liquid, and means for maintaining the liquid in the jacket at a substantially constant temperature.

2. Apparatus for conditioning shoe filler, which comprises a reservoir having a forwardly sloping floor, a basin projecting forwardly from the lower portion of said reservoir, a wedge-shaped heat distributing member projecting laterally from a wall of the reservoir, a jacket for liquid surrounding and underlying the reservoir and means for maintaining said liquid at a substantially constant predetermined temperature. 80

3. Apparatus for conditioning shoe filler, comprising a reservoir for filler material, a basin projecting from the lower portion of said reservoir, a jacket for heat-distributing liquid surrounding and underlying said reservoir and means for maintaining said liquid at a substantially constant temperature, said means including an electric heating unit against the bottom jacket, a second heating unit contiguous to a portion of said jacket, and a thermostat for automatically controlling the current supply to said second heating unit in accordance with the temperatures of the liquid in said jacket. 90

4. Apparatus for conditioning shoe filler, which comprises a reservoir for filler, a basin projecting forwardly from the lower part of said reservoir, a thin jacket on the sides and bottom of said reservoir, an oily liquid in said jacket, and means for maintaining said liquid at a substantially constant temperature. 100

5. Apparatus for conditioning shoe filler, which comprises a reservoir for filler, a basin projecting forwardly from the lower part of said reservoir, said reservoir having triple side walls consisting of an inner, a middle and an outer shell, heat insulating material between the outer and middle shells, and liquid between said middle and inner shells, and means for maintaining said liquid at a substantially constant temperature. 110

6. Apparatus for conditioning shoe filler, which comprises a reservoir having a forwardly sloping floor with a Monel metal surface, a basin projecting forwardly from the lower portion of said reservoir, said basin having a substantially horizontal floor which is a continuation of the sloping floor of said reservoir, and means for heating said floors. 115

7. Apparatus for conditioning shoe filler, which comprises a reservoir for shoe filler having an inner and an outer wall, said inner wall having a reentrant portion projecting inwardly, and a jacket for heat-distributing liquid adjacent to said inner wall including the reentrant portion thereof. 125

8. Apparatus for conditioning shoe filler, comprising a reservoir for shoe-filling material having a forwardly sloping floor, a basin projecting forwardly from the lower portion of said reservoir, a wedge-shaped heat-distributing member projecting forwardly from the rear wall of said reservoir, and a jacket for heat-distributing liquid behind the surfaces of said member which are exposed to the interior of said reservoir. 130

9. Apparatus for conditioning shoe filler, comprising a reservoir for filler material, a basin projecting from the lower portion of said reservoir, a jacket for heat-distributing liquid surrounding and underlying said reservoir, and means for heating said liquid, said heating means including a plurality of electrical heating units 140 and a thermostat responsive to the temperature of said liquid for turning on and off one of said heating units. 145

MELVIN O. JENNINGS.
